UNITED STATES PATENT OFFICE.

JOHN A. LAMONT AND ALFRED WALCHER, OF CHICAGO, ILLINOIS, ASSIGNEES TO AMERICAN STEEL FOUNDRIES, OF CHICAGO, ILLINOIS, A CORPORATION OF NEW JERSEY.

METHOD OF FORGING YOKES.

Application filed August 22, 1919. Serial No. 319,113.

To all whom it may concern:

Be it known that we, JOHN A. LAMONT and ALFRED WALCHER, both citizens of the United States, residing at Chicago, in the county of Cook and State of Illinois, have invented certain new and useful Improvements in Methods of Forging Yokes, of which the following is a specification.

This invention relates to a method of forging yokes.

One of the objects of the invention is to improve and simplify the method of making yokes.

Another object is to forge yokes by a novel and practical method to meet the various commercial requirements.

These and other objects are accomplished by means of the method illustrated on the accompanying sheets of drawings, in which—

Figures 1 and 2 are vertical sectional views at right angles with respect to each other, of a die with a blank placed therein, before receiving any pressing action;

Figures 3 and 4 are similar sectional views of the die showing the blank therein after having been given a slight pressing action by means of a plunger filling the upper part of the die;

Figures 5 and 6 are similar sectional views showing the blank after it has been subjected to pressure by another plunger, by means of which the hooded portion of the yoke is formed;

Figures 7 and 8 are similar sectional views of the die, showing the yoke after it has been subjected to pressure by another plunger for forming the arms of the yoke;

Figure 9 is a fragmentary side elevation of the yoke after the hooded end thereof has had portions thereof sheared off;

Figure 10 is a similar view, showing the hooded end of the yoke after the same has been provided with apertures;

Figure 11 is a fragmentary side elevation and Figure 12 is a top plan view of the yoke after an internal shoulder has been removed therefrom; and

Figures 13 and 14 are a top plan view and a side elevation, respectively, of the completed yoke.

The various novel features of the invention will be apparent from the following description and drawings, and will be par-

ticularly pointed out in the appended claims.

The entire yoke is in one piece and formed from a single blank, the blank preferably being cut from a suitably shaped ribbon of metal, the blank then being heated to a good forging temperature, so that the metal will readily flow when subjected to pressure. After the metal blank is heated, the latter is placed in a die and is subjected to pressure by a plurality of different plungers for properly shaping the rear end of the yoke, then forming the hood, and then forming the arms, after which the yoke is sheared, punched and trimmed. All of these operations may be accomplished by one or two heatings of the metal forming the yoke.

Referring to the figures of the drawings, and particularly to Figures 1 to 8 inclusive, it will be noted that we have shown a die 10, the vertical sections of which are taken at right angles with respect to each other. For example, Figure 1 shows the die 10, with its narrow portion in section; and Figure 2 shows the same die with its broad portion in section. The die is provided with oppositely arranged shoulders 11 for receiving the shoulder portions 12 of the metal blank 13, which blank, if desired, may be a piece cut from a metal ribbon of the section shown in Figure 1.

It will be noted that the original section of the blank as shown in Figure 1 has upper and lower faces 14 and 15 respectively, parallel with respect to each other and also parallel with the faces of the shoulders 12, the sides 16 of the blank diverging upwardly from the shoulder portions 12 to the upper face 14. The lower portion of the die 10 has a bottom face 17, from which the sides 18 diverge upwardly, terminating in vertical parallel side faces 19, which join the shoulders 11, from which side faces 19' diverge upwardly, terminating in vertical faces 20.

In the other section of the die, as shown in Figure 2, the side faces 21 are vertical substantially throughout their length and terminate at the bottom in elliptical curves 22 which form corners of the die.

The metal blank 14, heated to the proper temperature, is placed in the die 10, as shown in Figures 1 and 2, whereupon a plunger 23, filling the entire upper opening of the die, descends upon the blank 14, subjecting the

latter to pressure and forcing the metal down into the extreme lower end of the die to form the curved rear end 24 of the yoke, and otherwise pressing the blank snugly 5 against all surfaces of the die, as shown in Figures 3 and 4. A differently shaped plunger 25 is then forced down into the blank 13, causing the sides of the blank to flow upwardly around the plunger 25 and 10 along the sides of the die 10, forming the hooded end of the yoke, which includes side plates 26 and a top and bottom plate 27 connecting the same, as shown in Figures 15 5 and 6. The plunger 25 used in this step has shoulder 25^a on two sides to limit the upward flow of the metal forming the top and bottom plates 27 of the yoke as shown in Figures 5 and 6.

20 A rectangular prismatically shaped plunger wider in one direction than the other and has a sliding fit with the die side wall 19 and with the inner sides of the arms 28 is then pressed down into the die and into engagement with the blank, causing the 25 metal to flow upwardly around the plunger and along the sides of the die to form the upper and lower arms 28 of the yoke, as shown in Figures 7 and 8. The side plates 26 then have their triangular portions 26^a 30 trimmed off as shown in Figure 9; whereupon, said side plates 26 are punched to provide the usual registering openings 29, as shown in Figure 10. The shoulders 30 formed in the hood of the yoke, as shown in 35 Figures 5 to 8 inclusive, are then punched or sheared, leaving clean interior portions without obstructions, as shown in Figures 11 and 12, the completed yoke being shown in Figures 13 and 14.

In this method of forming a yoke, but a 40 single blank is used to form an integral structure, including the arms and hooded portion and their connecting parts.

It is our intention to cover all modifications of the method falling within the 45 spirit and scope of the following claims.

We claim:

1. The method of forging a yoke which consists in mounting a blank in a die, forcing the metal of said blank snugly against all 50 surfaces of said die and then forcing a plunger into said blank, causing the sides of said blank to flow around said plunger to form the hooded end of said yoke.

2. The method of forging a yoke which 55 consists in mounting a blank in a die, forcing the metal of said blank snugly against all surfaces of said die and then forcing a plunger into said blank, causing the sides of said blank to flow around said plunger to 60 form the hooded end of said yoke, and then pressing a rectangular, prismatically-shaped plunger into said die and into engagement with the blank to cause the metal to flow around the plunger along the sides of the 65 die to form the upper and lower arms of said yoke.

3. The method of forging a yoke which consists in heating a blank, subjecting said blank to pressure between a die and various 70 plungers to shape the rear end of the yoke, the hood and the arms, then shearing the yoke, punching and trimming same.

Signed at Chicago, Illinois, this 19th day of August, 1918.

JOHN A. LAMONT.
ALFRED WALCHER.
